CLAIM

I claim the ornamental design for a pet harness, as shown and described.

DESCRIPTION

FIG. 1 is a perspective view of a pet harness, showing a first embodiment of my new design in a fitted configuration; FIG. 2 is a perspective view of the design of FIG. 1, illustrated in a flat configuration;

FIG. 3 is a left-side elevational view of the design of FIG. 2; FIG. 4 is a right-side elevational view of the design of FIG. 2; FIG. 5 is a front elevational view of the design of FIG. 2; FIG. 6 is a rear elevational view of the design of FIG. 2;

FIG. 7 is a top plan view of the design of FIG. 2; FIG. 8 is a bottom plan view of the design of FIG. 2;

FIG. 9 is a perspective view of the design of a second embodiment of my new design in the fitted configuration;

FIG. 10 is a perspective view of the design of FIG. 2, illustrated in the flat configuration;

FIG. 11 is a left-side elevational view of the design of FIG. 10; FIG. 12 is a right-side elevational view of the design of FIG. 10;

FIG. 13 is a front elevational view of the design of FIG. 10; FIG. 14 is a rear elevational view of the design of FIG. 10; FIG. 15 is a top plan view of the design of FIG. 10; and, FIG. 16 is a bottom plan view of the design of FIG. 10.

The broken lines showing a pet in FIGS. 1 and 9 depict environmental matter and form no part of the claimed design. The remaining broken lines represent stitching, and are part of the claimed design.
